UNITED STATES PATENT OFFICE

125,665

DESIGN FOR A DRESS ENSEMBLE

Harry Lasoff, Boston, Mass.

Application December 16, 1940, Serial No. 97,375

Term of patent 3½ years

To all whom it may concern:

Be it known that I, Harry Lasoff, a citizen of the United States, residing in Boston, in the county of Suffolk and State of Massachusetts, have invented a new, original, and ornamental Design for a Dress Ensemble, of which the following is a specification, reference being had to the accompanying drawings, forming part thereof.

Fig. 1 is a front view of a dress ensemble showing my new design.

Fig. 2 is a rear view of Fig. 1.

Fig. 3 is a front view of the dress member of the ensemble, and

Fig. 4 is the rear view thereof.

I claim:

The ornamental design for a dress ensemble, substantially as shown.

HARRY LASOFF.
